UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

FINISHING DEVICE FOR CURVED STEREOTYPE PRINTING-PLATES.

1,286,478.

Specification of Letters Patent.

Patented Dec. 3, 1918.

Application filed September 16, 1913, Serial No. 730,072. Renewed September 6, 1918. Serial No. 252,973.

To all whom it may concern:

Be it known that I, HENRY A. WISE Wood, a citizen of the United States, residing at New York, in the county of New York and 5 State of New York, have invented a new and useful Finishing Device for Curved Stereotype Printing-Plates, of which the following is a specification.

This invention relates to a finishing device 10 for semi-cylindrical stereotype printing plates of the type in which the plates are fed down an inclination partly or wholly by gravity.

Many features of the invention constitute 15 improvements over the finishing device set forth in my Patent No. 1,283,973, patented September 4, 1917, filed June 25, 1912.

The principal objects of the invention are to provide a one man machine occupying 20 small space, in which the advantages of finishing the plates while traveling down an incline can be secured conveniently in conjunction with a vertical casting chamber which will automatically take care of its own refuse and in which the plate can be inspected readily between operations; to provide 25 for taking the semi-cylindrical plate from a vertical casting chamber, or other support, swinging the plate from the core on inclined temporary tracks and then feeding it therefrom down through an inclined finishing device and delivering it cool and dry; to provide a practicable and efficient construction of temporary receiving tracks for holding the plate after it is delivered from 30 the mold in position in alinement with the finishing mechanism capable of feeding the plates thereto by gravity so that no conveying mechanism will be required; to provide positive means for controlling the descent of 35 the plate into the inclined finishing mechanism; to provide means for lifting the tail severed from the plate out of the shaving arch and delivering it to a conveyer; to provide improvements in means for adjusting 40 the motion of the movable plate supporting tracks within the shaving arch; to facilitate the inspection of the plates throughout their travel through the machine; and to provide improvements in the details of construction 45 of the above mentioned features and in the cooling device to which the plate is delivered from the finishing mechanism.

Reference is to be had to the accompanying drawings in which—

Figure 1 is an elevation of a finishing 55 machine constructed in accordance with this invention showing its relationship to a casting mechanism;

Fig. 2 is a plan of a portion of the driving mechanism therefor; 60

Fig. 3 is an end elevation of the temporary tracks for receiving the plates from the core;

Fig. 4 is a side elevation of a portion of 65 the finishing arch and connected mechanism on enlarged scale, partly broken away to show the interior construction and in section along a central, longitudinal, vertical plane;

Fig. 5 is a transverse, sectional view on the line 5—5 of Fig. 4;

Fig. 6 is a plan of part of the cutter operating mechanism in the finishing arch; 70

Fig. 7 is an end elevation of the finishing mechanism looking in the direction of the axis of the finishing arch;

Fig. 8 is a side view of the lower portion 75 thereof shown partly in section;

Fig. 9 is a side elevation of a portion of the arch with parts in section showing the tail ejector;

Fig. 10 is an end view of a portion of the 80 tail ejector;

Fig. 11 is an end view of the arch showing the chute for delivering a severed tail therefrom; and

Fig. 12 is a transverse sectional view of 85 the cooling trough.

Referring especially to Fig. 1, the invention is shown as applied to a type of stereotype machine in which a frame A is provided with a movable back B, and a cylindrical core C, constituting a mold. This back is intended to move away from the core to permit the core to turn half way around on its own axis so as to deliver the plate from the back and permit the plate to 90 be taken away from the core. The mechanisms for operating the core and back are not described herein as they do not constitute a part of this invention. The core constitutes a support for a curved stereotype 95 plate which is to be taken therefrom and finished.

For the purpose of operating the machine, a motor 10 is shown in Fig. 2 transmitting

- power by a flexible chain 11 driven from a pinion 12 fixed to the motor shaft 13 and rotating with it. This chain meshes with a gear 14 keyed to the main driving shaft 15. 5 This shaft has formed on one end a worm 16 meshing with a worm wheel 17, which is keyed to a shaft 18 at one end. A gear 19 keyed to the shaft 18 at its other end, meshes with a gear 20 on a cam shaft 21. The cam shaft is provided with a tail ejector groove cam 23 and with a gear 25. This gear operates a gear 26 keyed to a crank shaft 27 for operating a swinging frame D for delivering the plate from the core. 10
- 15 Meshing with the gear 20 is a pinion 29 on a shaft 31. On this shaft is a beveled gear 32 meshing with a beveled gear 33 on an inclined shaft 34. This shaft 34 is provided with a beveled gear 35 which meshes 20 with a beveled gear 36 on a stud 37, carrying a toothed wheel 38, shown in Fig. 7, the purpose of which will be described herein-after.
- 25 On the shaft 15 is a worm 40 driving a worm wheel 41 on a shaft 42, which by gears 43 drives an elevator shaft 44 having a pair of worms 45 thereon for operating the elevator.
- 30 On the shaft 15 is a worm 46 operating a worm wheel 47 on a shaft 48. This shaft is provided with a worm 49 operating a worm wheel 50 on an inclined hollow shaving shaft 51 which carries an adjustable shaving blade 59. Passing axially through 35 this shaving shaft 51 is a cutter shaft 52. This is operated from a shaft 53 by gears 54 and is provided with a beveled gear 55 which operates a saw 56 in the manner set forth in my above identified application for 40 patent. The shaft 53 is operated by gears 57 from the shaft 15. This shaft 53 is furnished with a handle 58 for operating the machine by hand.
- 45 On the shaft 27 is keyed an arm 60 connected by a link 61 with the frame D. This frame is swung on a pair of studs 62 mounted above the core in line with the axis of the plate while supported in position for shaving and is provided with supports 63 50 for supporting the cast plate P in a manner which I have described in a co-pending application on machine for casting and delivering curved stereotype printing plates, filed Sept. 16, 1913, Serial No. 790,070.
- 55 Upon each rotation of the shaft 27, the delivering device D delivers a cast plate from the core and swings it upwardly about the axis of the studs 62. As this plate moves upwardly, its edges engage a pair of 60 intermediate tracks. These consist of a plurality of pairs of pivoted arms 65 and 66 keyed to shafts 67. These shafts are loosely mounted in brackets 68 attached to the frame A. The normal position of the arms 65 and 65 66 is such that a plate resting on them is

properly aligned with the finishing arch F of the machine. They are held in normal position by torsional springs 69. These springs are loosely coiled around the shafts 67 and attached to the brackets 68 at one 70 end. Each of these springs is attached to a stop lever 70, one of which is keyed to each of the shafts 67 and suitably formed to engage with the foot of one of the brackets 68.

75 The pivoted arms 66 are formed with projections or tracks 71 at their ends adapted to engage the outside surface of the tail T of the plate so as to cause the tail to spread the tracks when the plate is swung up into 80 inclined position. As the plate moves beyond these tracks the springs cause them to move back under the edges of the plate and support it. Projections 72 on the arms 65 are formed shorter than the projections 85 71 on the arms 66 so that they will not actually engage the outside curved surface of the plate but will swing under them after the plate moves up into position to serve as temporary tracks. This is to prevent the 90 marring of the printing surface.

When a plate is thus left on these intermediate tracks, it is obviously in inclined position so that it is capable of sliding down by gravity into the finishing arch F. 95 As it moves into the arch, a rack P' cast on the concave surface of the plate engages the wheel 38. As this wheel is positively driven at a definite speed, it will be obvious that the plate will be fed downward at that 100 speed as long as the teeth of the wheel engage the rack on the plate. The plate continues to move down into the arch until stopped as will appear hereinafter.

As the plate descends into the arch its 105 edges engage a stationary track 75 along one side of the arch and a movable track 76 along the other side. These tracks are in alignment with the studs 62. For the purpose of moving this track, the following 110 mechanism is provided: On the shaft 27 is a cam 80. This operates a roller 81 adjustably mounted on one arm of a lever 82. A spring 83 is provided for keeping this roller in contact with the cam. The adjustment of 115 the roller is effected by adjusting screws 84. Pivotally mounted on the top of the other arm of the lever 82 is a plate 85 adapted to be adjusted vertically by an adjusting screw 86 bearing on the end of this arm of the 120 lever. Passing down through openings in the plate 85 of the lever 82 is an operating rod 87. A spring 88 surrounding the rod 87 rests on the plate 85 and engages a collar 89 fixed on the rod near the top. A 125 collar 90 is rigidly fixed to the bottom of this rod below the lever 82 to prevent the spring from disarranging the relative relations of the parts.

The top of the rod 87 is pivoted to a lever 130

91 keyed to a pivotally mounted shaft 92. This lever or arm is also pivoted to a rod 93 which is connected by a pivoted stud 94 with a lifting arm 95. This arm in turn is pivoted on a stud 96 mounted on the arch. The movable track section 76 is also pivoted on the stud 94. Upon each rotation the cam 80 actuates the lifting lever 95 to cause the same to engage with the edge of the plate. This pushes the plate into contact with the arch along one edge and swings it into a firm seat in the arch. The last named part of this mechanism together with the stationary track 75 are shown in my above mentioned application for patent but some of the operating connections are added thereto.

The spring 88 acts as a cushion in the mechanism between the cam and the lifting lever, so that any excess motion other than that necessary to lift the plate into contact with the arch and hold it there is taken up by the spring. The adjustment is arranged so that the compression of the spring can be adjusted conveniently to a suitable degree without disarranging the relative positions of the lever 82 and the lifting lever 95.

It will be understood in accordance with my previous application for patent above specified that the end of the lifting lever 95 is provided with a notch 97 for engaging the edge of the plate and lifting it up into proper position in the arch and that the track 76 which supports the plate when it is in its lower position is caused to slide along a supporting shelf 98 on the frame below the arch.

In accordance also with my above mentioned previous application for patent, the shaving blade 59 and tail cutting saw 56 operate to shave out the interior of the plate and cut the tail off.

For the purpose of stopping the plate in the right place as it descends along the arch supported on the tracks 75 and 76, the following mechanism is provided: On the shaft 51 is a cam 102 operating a roll 103. This roll is mounted on a stud on a sliding yoke 104. The yoke is loosely mounted on a sliding block 105 fastened to a brace constituting a part of the frame-work A of the machine. For the purpose of keeping the roll in contact with the cam, a tension spring 106 is provided attached to the brace carrying the sliding block 105 and to the yoke 104.

In this way with each rotation of the shaving blade a stop piece 107 on the top of the yoke 104 is held during a certain period in position to intercept the plate supported on the tracks 75 and 76 and sliding down them through the arch. This stop piece 107 thus positions the plate in the arch so that it can be elevated into the proper position therein by the plate lifters 95 just before the shaving blade gets around into

position for operating on the inside of the plate.

The stop is actuated by the cam to rise with the plate until the latter is held in contact with the arch and then to move upwardly past the plate to allow the shaving knife to rotate clear under the stop. Then the stop descends to a position in which it intercepts the plate as the plate is lowered in the arch back on the tracks 76, thus preventing the plate from sliding out of the arch during this operation. Then it descends below the edge of the plate so as to allow the plate to slide out of the arch freely by gravity.

It will be understood, of course, that in the discharge of the plate from the arch, it is not accompanied by the tail which has been severed by the saw 56. For the purpose of ejecting the tail, the cam 23 on the shaft 21 has a groove in which operates a roll 110 on an arm 111, loosely mounted on a shaft 112. Also attached to the arm 111 is an arm 113 so that these two arms constitute a lever. This arm 113 is pivoted to a tail ejector yoke 115 which has a stud 116 attached to it. This stud is loosely mounted on the end of a tail ejector yoke lever 117, loosely mounted on a stud 117a.

The tail ejector yoke 115 has two upwardly extending arms on which are loosely mounted a pair of studs 119. On these studs are pivoted two tail ejector brackets 120 and 121, each having an inwardly projecting foot 122 for supporting the severed tail. These arms are spaced widely apart to allow the plates to slide down between them into the arch. The feet 122 are arranged at different heights to give the tail a slight tilt to one side.

The pivoted brackets 120 and 121 are each provided with an extension 123 extending below the pivots and adapted to engage fixed lugs 124 on the yoke to limit the inward motion of the upper ends of the brackets 120 and 121. A pair of flat springs 125 are fixed to the yoke and extend up above the pivots 119 against the outer sides of the brackets for the purpose of normally holding said brackets in their innermost positions with their projections 123 against the lugs 124 as shown in Fig. 10.

Once during each rotation of the shaft 21, the tail ejector yoke 115 is raised. This is timed so that this operation takes place immediately after the tail is severed from the plate and it brings the feet 122 upwardly under the severed edges of the tail and lifts the latter above the arch. On account of one foot 122 being higher than the other, this swings the tail about one edge to clear the parts within and then raises it. This causes the brackets to slide upwardly along the face of the arch until the tail has passed the face of the arch and is free to slide by

gravity over the arch as shown in Fig. 9, and along a chute 126 formed on top of the arch to receive it.

This chute as shown in Fig. 11 extends 5 down along the outside of the arch at an inclination and is provided with a projection 127 on one lower side thereof which one advance corner of the tail T engages as it slides down. This causes the tail to be 10 turned around a quarter of a turn so that one of its straight edges is foremost. Then it slides down an incline 128 which also forms a part of the chute and is at an angle to the upper portion thereof so as to be less 15 abrupt. At the bottom of this incline, one advance corner of the tail engages a projection 129 on the same side. This causes it to turn again so that the heavier of its curved edges is at the bottom. In this way its 20 descent down the incline is interrupted and it will not gather much momentum. Then it slides by gravity over an incline 130 into a conveyer 131 operated by the worms 45. In passing into the conveyer it is stopped 25 by a fixed plate 132.

Returning now to the plate which has been discharged from the finishing arch, it will be seen that it slides down into a cooling device G as shown in my above mentioned application for patent. This cooling device is provided with a plate 133 at the end over which the finished plate slides as it passes 30 into the cooling device. The stereotype plate sets down over this plate 133 and the latter 35 acts as a stop to prevent the discharge of water beyond the end. At the other end the stereotype plate engages a plate 134 which is yieldingly mounted as indicated. Thus both ends of the printing plate are closed to 40 prevent splashing.

The printing plate in descending into the cooler engages a lever 135 which operates a valve 136 and permits the passage of water into a pipe 137 which is connected to a spray 45 pipe 138 inside the plate for the purpose of cooling the same. The shaving arch is also shown as being cooled by means of a pipe 140 for supplying the fluid to a chamber 141 therein and having a discharge 142 which 50 supplies the pipe 137. The water from the cooling device is discharged through a drain pipe 143.

During this time the printing plate is supported on a pair of tracks 145 having inside them a pair of adjustable sizing stops 146 mounted on platforms 147 and adjusted by screws 148. This is for sizing the plate so that the concave surface will be of proper diameter to fit the press cylinder when the 55 plate is cooled. This mechanism is provided because the application of a cooling fluid against the inside of a curved plate causes the concave surface to be cooled first and to contract. The outside or convex surface 60 retains its heat longer and does not con-

tract simultaneously with the concave surface. Thus during the cooling process the first action would be to decrease the diameter of the plate temporarily and then as the diameter of the plate becomes uniform throughout, the diameter would increase. The stops 146 prevent this alternate increase and decrease and keep the diameter uniform at all times so that it will fit a cylinder of a press. The usual increase is merely a restoration to 75 normal and is prevented here by eliminating the decrease.

To recapitulate, the operation of the machine briefly is as follows:—A plate cast in the casting box is turned on the core to a 80 position outside the box and swung upwardly into the temporary tracks 72 which yield to permit the plate to enter them and then swing inwardly under the edges of the plate to prevent its being moved back to the 85 mold upon the return of the swinging frame D. As this frame starts back toward the mold the freed plate moves down these temporary tracks by gravity until the rack-teeth cast on its inner surface engage the 90 wheel 38. This, being positively driven, absolutely controls the further passage of the plate down into the finishing arch F.

On entering the arch, the plate rests on the tracks 75 and 76 until it engages the stop 95 107 at the end of the arch and then the cam 80 operates to force the lifting levers 95 up and cause the plate to be clamped in the arch. It is at this time that the shaving blade turns around to operative position and 100 also the tail cutting saw.

As soon as the shaving and tail cutting operations are completed the tail ejector operates to discharge the tail down through the chute into the elevator. At the beginning 105 of this operation the stop, having previously been raised above the plate, now descends and holds the plate in the arch while the lifting levers 95 also descend. Then the stop drops below the edge of the plate and 110 the plate is free to slide out of the arch by gravity into the cooling device. After it is cooled it is lifted from the cooling device by hand. It is to be noted that certain features shown herein are also shown in my 115 companion case of even date herewith, Serial No. 790,070, but are claimed therein only in connection with features of the casting mechanism, the said casting mechanism not being included in the claims in this case. Any matter contained herein and also disclosed in my prior Patent No. 1,269,239 patented June 11, 1918, is not claimed herein, as it is claimed in that case. The cooling device by itself is not claimed herein as it 125 is claimed in my copending divisional application Serial No. 207,337 filed Dec. 15, 1917.

Although I have illustrated and described only a single embodiment of the invention 130

and shown it as applied to the mechanism shown in my above identified application for patent, I am aware of the fact that many modifications can be made in the construction herein shown, and that it can be applied to other types of stereotyping machinery without departing from the scope of the invention as expressed in the claims. Therefore, I do not wish to be limited in these respects, but what I do claim is:—

1. The combination with a support for a stereotype printing plate, of a frame adjacent thereto having means thereon for engaging a plate, and means for moving the top of said frame, with a plate thereon, away from said support to an inclined position.
2. The combination with a support for a printing plate, of a frame pivoted to swing on a transverse axis at the bottom, and means on the swinging frame for engaging a plate on said support and taking the plate away from the support with the swinging frame to an inclined position.
3. The combination with a vertical convex support for a concave printing plate, of a frame pivoted at the top of said support to swing on a transverse axis, and means on the frame for engaging a plate on said support and taking the plate away from the support with the frame.
4. The combination with a vertical convex support for a concave printing plate, of a swinging frame pivoted at the top of said support in line with the axis thereof to swing on a transverse axis, and means on the swinging frame for engaging a plate on said support and taking the plate away from the support with the swinging frame.
5. In a machine for finishing stereotype printing plates, the combination with a support for a concave printing plate, of a frame mounted adjacent thereto and movable away from the support at one end through a small angle, means on said frame for engaging the plate and separating it from said support when the frame moves away from the support, and tracks in alinement with said separating means in its final position for receiving the plate from said separating means.
6. In a machine for finishing stereotype printing plates, the combination with a frame, and means connected therewith for engaging a plate supported on a support and removing it therefrom, of yielding tracks in position to engage and support the plate.
7. In a machine for finishing stereotype printing plates, the combination with a frame, of means thereon for engaging a plate while on a convex support, means for moving said frame away from said support, and yielding tracks in position to receive the edges of said plate between them and to close upon the plate after it has passed them, whereby when the swinging frame is moved
8. The combination with a vertical convex support for a concave printing plate, of a swinging frame pivoted at the end of said support to swing on a transverse axis, and means on the swinging frame for engaging a plate on said support and taking the plate away from the support with the swinging frame, and inclined tracks in alinement with the axis on which said frame swings for receiving the plate therefrom.
9. In a machine for finishing stereotype printing plates, the combination with a frame for conveying a curved printing plate, with a set of tracks for receiving the plate from said frame, said tracks comprising pivoted members, yielding means for normally holding said members substantially in the path of travel of the edges of the plate, whereby when the plate moves between the tracks it will swing them away from each other and permit them to swing back under the edges of the plate to support it.
10. In a stereotype plate finishing machine, the combination of the frame, a pair of shafts mounted to turn on the frame, a pair of tracks supported by said shafts and having feet extending inwardly toward each other, and means for moving the convex surface of the plate inwardly between said projecting portions of the tracks, whereby the plate will engage the tracks and force them apart, and means for moving the projecting ends of the tracks inwardly to engage under the edges of the plate.
11. In a stereotype plate finishing machine, the combination of the frame, a pair of shafts mounted to turn on the frame, a pair of tracks on said shafts and having feet extending inwardly toward each other, means for moving the convex surface of the plate inwardly between said projecting portions of the tracks, whereby the plate will engage the tracks and force them apart, springs for moving the projecting ends of the tracks inwardly to engage under the edges of the plate, and another pair of tracks fixed to the same shafts and having inwardly extending feet shorter than the feet on the first named tracks to prevent their engaging the type surface of the plate.
12. In a stereotype plate finishing machine, the combination of the frame, a pair of tracks having feet extending inwardly toward each other, means for moving the projecting ends of the tracks inwardly to engage under the edges of the plate, and another pair of tracks having inwardly extending feet shorter than the feet on the first named tracks to prevent their engaging the type surface of the plate.
13. In a stereotype plate finishing machine, the combination of a pivoted arm having a transverse projection on the end

thereof, yielding means for swinging said arm in the direction in which the projection extends from it, means for limiting the swinging motion in that direction, whereby 5 when a plate is moved against said arm the arm will yield and will thereafter move beyond the edge of the plate and serve as a support therefor.

14. In a stereotype plate finishing machine, the combination with an inclined arch and finishing mechanism therein, of means for moving a plate from a vertical support, and an intermediate track inclined toward the arch and in position for receiving the 10 plate from said removing means and directing it into the arch, said intermediate track comprising swinging arms having projections for engaging and supporting the plate, and yielding means for holding the arms in 15 position to engage the plate.

15. In a stereotype plate finishing machine, the combination with an inclined arch and finishing mechanism therein, of means for moving a plate from a support, and an 20 intermediate track inclined in line with the arch and in position for receiving the plate from said removing means and directing it by gravity directly into the arch.

16. In a stereotype plate finishing machine, the combination with an inclined shaving arch, of inclined tracks beyond the entrance of said arch for directing plates thereto, a toothed wheel between the arch and tracks, a shaft, means connected with 30 said shaft for finishing the plate in the arch, and means connected with said shaft for operating said toothed wheel positively.

17. In a stereotype plate finishing machine, the combination with an inclined arch 40 for receiving a plate to be finished, means connected with said arch for finishing the plate while in the arch, a toothed wheel adjacent to the entrance to the arch in position to engage a plate while under the arch, and 45 means connected with the finishing means for positively controlling the rate of descent of the plate in the arch.

18. In a stereotype plate finishing machine, the combination with an inclined 50 shaving arch, means connected therewith for finishing a plate, and means adjacent to the upper end of said arch for positively controlling the speed of the plate entering the arch.

55 19. In a machine for finishing stereotype printing plates, the combination of an inclined shaving arch, with a pivoted plate lifting device therein, means for operating the plate lifting device, a spring in said 60 plate lifting device coöperating with said means, and means for adjusting the compression of the spring.

20. In a stereotype printing plate finishing machine, the combination with an arch, 65 a plate lifting lever in the arch, a rod for

operating said lever, a lever for operating the rod, a spring between the last named lever and the rod, a plate movably mounted on the last named lever for engaging the end of said spring, and means for adjusting 70 the position of the plate along the rod.

21. In a stereotype printing plate finishing machine, the combination with an arch and a plate lifting lever therein, of a rod 75 pivotally connected with said lever for operating it, a cam lever, a plate pivoted on the cam lever, said rod passing through said plate and cam lever, a spring resting on the plate at one end, means at the other end of said spring for transmitting its pressure to 80 the rod, and means for adjusting the plate about its pivot and along the rod.

22. In a stereotype printing plate finishing machine, the combination with an arch and a plate lifting lever therein, of a rod 85 pivotally connected with said lever for operating it, a cam lever, a plate pivoted on the cam lever, said rod passing through said plate and cam lever, a spring resting on the plate at one end, means at the other end of 90 said spring for transmitting its pressure to the rod, means for adjusting the plate about its pivot and along the rod, a washer fixed on the rod beyond the cam lever, a cam for operating the cam lever, and a roll adjustably mounted on the cam lever for engaging 95 the cam.

23. In a stereotype printing plate finishing machine, the combination of an inclined arch for receiving a plate to be finished, a 100 finishing device extending into the arch, a stop at the bottom of the arch, and means for moving the stop into a position to engage a plate as it enters the arch, then lifting the stop along the face of the arch and 105 beyond the inner edge of the plate, and for then drawing the stop back below the edge of the plate.

24. In a stereotype printing plate finishing machine, the combination of an inclined arch for receiving a plate to be finished, means in the arch for receiving the plate and for thereafter raising it in the arch in order to be finished, and then dropping it back to its original position to be discharged, 110 a stop, and means for moving the stop into a position to engage the lower edge of the plate when it first enters the arch, raising it with the plate as the plate is raised in the arch and beyond the inner edge of the 115 plate when the plate is in its highest position, and thereafter withdrawing the stop with the plate as the plate descends in the arch, and drawing it down beyond the inner edge of the plate to permit the plate to be 120 discharged from the arch.

25. In a stereotype printing plate finishing machine, the combination of an arch for receiving a plate to be finished, means for severing the tail from the plate, and means 130

- for thereafter lifting the tail along the upper face of the arch and discharging it therefrom.
26. In a stereotype printing plate finishing machine, the combination of an inclined arch for receiving a plate to be finished, means for severing the tail from the plate, a tail ejector yoke, and brackets movably mounted on said yoke for engaging the edges of the tail and lifting them to discharge the tail.
27. In a stereotype plate finishing machine, the combination with a shaving arch, and means for severing a tail from a plate at the upper face of said arch, of a tail ejector yoke, brackets on said yoke for engaging the straight edges of said tail, and means for raising said yoke to lift the tail along the face of the arch and discharge it therefrom.
28. In a tail ejecting device for a stereotype plate finishing machine, the combination of a reciprocable yoke, and a pair of brackets pivotally mounted on said yoke projecting inwardly and having feet on the ends thereof for engaging and supporting the straight edges of a tail.
29. In a tail ejecting device for a stereotype plate finishing machine, the combination of a reciprocable yoke, a pair of brackets pivotally mounted on said yoke projecting inwardly and having feet on the ends thereof for engaging and supporting the straight edges of a tail, yielding means for forcing said brackets to swing inwardly on their pivots, and positive means for limiting said inwardly swinging motion.
30. In a tail ejecting device for a stereotype plate finishing machine, the combination of a movable yoke having upwardly extending arms to permit the passage of a printing plate through the yoke, brackets pivoted to the tops of said arms and extending upwardly and inwardly therefrom, and means on the ends of the brackets for supporting the tail of a plate.
31. In a stereotype printing plate finishing machine, the combination with an inclined arch for receiving a plate to be finished, means for finishing a plate in the arch and for simultaneously severing the tail from the plate, and means for thereafter lifting the tail along the upper face of the arch and discharging it therefrom.
32. In a stereotype printing plate machine, the combination with an inclined arch for receiving a plate, means for severing the tail from the plate, means for thereafter lifting the tail along the upper face of the arch and discharging it therefrom, and a chute extending down along the arch for receiving the tail, said chute having means for turning the tails as they descend therethrough by gravity.
33. In a stereotype printing plate making machine, the combination with means for severing the tail from a plate, of an inclined chute in position for receiving the tail, said chute having projections on opposite sides for engaging the tail and turning it as it descends.
34. In a stereotype plate finishing machine, the combination with an inclined finishing arch, of a cooling device arranged at the lower end thereof to receive plates therefrom and having tracks at an angle to the inclination of the arch for supporting the edges of the plates throughout their length.
35. In a machine for finishing stereotype printing plates, the combination with an inclined finishing arch, of a cooling device for the plates having straight horizontal tracks for receiving the plates from the arch and supporting their edges.

In testimony whereof I have hereunto set my hand, in the presence of two subscribing witnesses.

HENRY A. WISE WOOD.

Witnesses:

B. M. STOEBER,
LILLIAN C. JONES.
